United States Patent Office

Des. 215,727
Patented Oct. 28, 1969

215,727

POST BASE

Tyrell T. Gilb, 111 El Camino Real,
Berkeley, Calif. 94705

Filed Nov. 7, 1968, Ser. No. 14,348

Term of patent 14 years

Int. Cl. D25—01

U.S. Cl. D28—1

FIGURE 1 is a perspective view of the post base showing my new design;

FIGURE 2 is a plan view of my new design; the broken lines indicating a post and bolts and nails for securing the post to the post base.

FIGURE 3 is an end elevation view of my new design; the broken lines indicating a post, nails and bolt—the horizontal broken line indicating the top elevation of a portion of the concrete foundation.

FIGURE 4 is a side elevation view of my new design; the broken lines indicating a post, nail and bolt heads.

The broken line showing of the post, bolts, bolt heads, nails, and concrete foundation are for illustrative purposes only and form no part of the claimed design.

I claim:

The ornamental design for a post base, substantially as shown and described.
